UNITED STATES PATENT OFFICE.

JOHN J. RAYNER, OF WASHINGTON TOWNSHIP, CARROLL COUNTY, MISSOURI, AS-
SIGNOR TO O. S. RAYNER, OF BRAYMER, MISSOURI.

REINFORCED BUILDING-BLOCK FOR CIRCULAR WALLS.

1,109,248.

Specification of Letters Patent.

Patented Sept. 1, 1914.

Application filed October 28, 1912, Serial No. 728,276. Renewed January 23, 1914. Serial No. 813,977.

To all whom it may concern:

Be it known that I, JOHN J. RAYNER, a citizen of the United States, residing in Washington township, in the county of Carroll and State of Missouri, have invented new and useful Improvements in Reinforced Building-Blocks for Circular Walls, of which the following is a specification.

My invention relates to reinforced building blocks for circular walls for use in the construction of silos, tanks, cisterns, reservoirs, and the like.

The object of my invention is to provide a reinforced building block, which when laid in a circular wall, will effectively coöperate with similar blocks for the reinforcement of the entire structure.

The preferred embodiment of the invention is hereinafter described and illustrated in the accompanying drawings.

In the drawings:—Figure 1 is a perspective view of several building blocks laid in a wall. Fig. 2 is a plan view of the reinforced building block. Fig. 3 is an elevation of the reinforced building block.

Referring to the drawings, 1 designates an arcuate building block having air spaces 2 divided by partition wall 3. The several portions of arcuate building block 1 are designated as follows:—4 is an end face, 6 is the other end face, 7 is the arcuate inner surface, 8 is the arcuate outer surface, and 9 and 10 are chamfered end surfaces.

Embedded in the building block 1 between arcuate outer surface 8 and the air spaces 2 is an arcuate reinforcing rod 11, having an eye 12 protruding from chamfered end surface 9 and a hook 13 protruding from chamfered end surface 10.

The blocks are preferably formed of cement, concrete, or similar plastic material, and are positioned in the wall by breaking joints in the usual manner.

In laying the blocks in the wall, end face 4 of one block is laid adjacent to end face 5 of another block, and hook 13 of one block

is pressed through eye 12 of the adjacent block. Hook 13 is then closed, forming an eye, and effectively joining the blocks together. The spaces formed by chamfered end surfaces 9 and 10 may then be filled with concrete, or the like, for the protection of the joint.

It will be seen from the foregoing description that my invention provides a reinforced building block which will coöperate effectively with similar building blocks for the reinforcement of a circular wall.

It is clear that changes in the details of construction may be made without departing from the spirit and scope of my invention.

Having thus described my invention, what I claim is:—

1. The combination in a reinforced building block for circular walls, of an arcuate building block having chamfered end faces, an arcuate reinforcing rod embedded in said arcuate building block, said arcuate reinforcing rod having a hook protruding from one of said chamfered end faces and an eye protruding from the other, said hook being adapted to enter an eye protruding from the chamfered end face of an adjacent block, and said eye being adapted to receive a hook protruding from the chamfered end face of another adjacent block, substantially as described.

2. The combination in a reinforced building block for circular walls, of an arcuate building block having chamfered end faces, a hook protruding from one of said chamfered end faces, an eye protruding from the other of said chamfered end faces, and an arcuate reinforcing rod formed integral with and connecting said hook and eye, substantially as described.

JOHN J. RAYNER.
